and Chemical Company, Los Angeles, Calif., a corporation of Delaware

Filed May 5, 1964, Ser. No. 79,823

Term of patent 14 years

(Cl. D44—15)

FIG. 1

FIGURE 2 is also a top perspective view of combined serving dish, handle and cover therefor but with the handle removed and a sealing cover in engagement therewith;

I claim:

The ornamental design for a combined serving dish, handle and cover therefor, as shown and described.
